INJECTION PUMP FOR INTERNAL
COMBUSTION ENGINES

Max Hurst, Stuttgart, and Otto Beck, Winterbach O/A Schorndorf, Germany, assignors to Robert Bosch Gesellschaft mit beschränkter Haftung, Stuttgart, Germany

Application June 30, 1939, Serial No. 282,260
In Germany July 30, 1938

16 Claims. (Cl. 103—41)

The invention relates to injection pumps for internal combustion engines of the type in which a piston is axially displaced within a cylinder to provide a pumping effect and can be rotated in the cylinder to adjust the pumping effect; and has especial reference to fuel injection apparatus for multicylinder internal combustion engines, wherein a control rod is arranged to effect simultaneous adjustment of the pumping effect of a plurality of pumping cylinders each supplying fuel to a cylinder of the internal combustion engine.

An object of this invention is the provision of a constructionally simple arrangement whereby individual adjustments of the fuel supply conditions of each separate cylinder may be effected.

A further object is to enable such an arrangement to be operated without the necessity of wholly or partially disassembling the pumps.

A still further object is to permit of adjustment by means of relatively simple tools, and without waste of time.

Other objects and advantages will become apparent in the following description of the invention, with reference to the accompanying drawings in which:

Figure 1 shows one form of construction, in section, at right angles to the driving shaft.

Figure 2 illustrates parts out of Figure 1 shown in perspective.

Figure 3 shows a further form of construction, in section, at right angles to the driving shafts.

Figure 4 illustrates parts out of Figure 3 shown in the same manner as those in Figure 2.

In a housing 1 of a separate pump, a plunger 4 is moved by a cam 2 through a cam-follower 3. The fuel supply, or alternatively, the return flow of fuel, is adjusted in known manner by rotative displacement of a piston 4, with consequent adjustment of the position of a helical edge 5 of the piston 4 in a cylinder 6. A diagonal toothed rod 7 common to all the pumps, is guided in the pump housing 1 and engages with a toothed quadrant forming part of a collar 8a of the intermediate membr 9, which is fitted over the cylinder. The member 9 is provided with vertical slots 10 at the end directed towards the drive. These slots receive projections 11 of the piston 4. A helical spring 12, serving as a return spring for the piston, abuts at one end on the spring plate 13 which rests against the piston, and at the other end on a plate 14 which rests against the shoulder 8b of the member 9. A pin 15, having an eccentrically disposed projection 16, passes through the housing 1. The projection 16 en-

gages in a groove 17 in the periphery of the collar 8a. The pin can be locked in any desired position by means of a threaded ring 18 and a sealing washer 19' which rests on a shoulder 19 of the pin 15.

Normally the fuel supply is uniformly adjusted for all the pumps by the displacement of the toothed rod 7 which causes the operating sleeves 9 to rotate all the pistons 4 by means of the coupling projections 11. If the fuel delivery of an individual pump is to be adjusted in relation to the other pumps, this is effected by angular displacement of the pin 15 after loosening the thread ring 18. This rotary movement of the pin 15 causes the eccentric projection 16 to rise or fall, carrying with it the control sleeve 9 with which it engages. On account of the diagonal toothing of the segment 8 which engages with the toothed rod 7, this axial displacement causes the intermediate member 9 to be rotated, thus causing angular displacement of the piston. When the piston has been adjusted so as to produce the desired alteration in the fuel delivery, the pin 15 is tightly locked in its new position in the housing by tightening the threaded ring 18.

The example of construction shown in Figure 3 differs from the first in that instead of the adjusting pin, a universally adjustable spindle 20 is disposed in a bore 20' running parallel to the axis of the piston. That end of the bore 20' which is remote from the drive is provided with a thread 26 to receive the threaded part 27 of the head of a spindle. A threaded locking ring 28 at the upper end serves to secure the spindle in the position into which it is adjusted from without. A screw cap 29 seals the end of the bore 20'. On that end of the spindle 20 which is turned toward the drive is fitted a sliding-plate 21 which is angularly displaceable but not axially displaceable in relation to the spindle. This sliding-plate 21 engages in a groove 17' in a partially toothed collar 22. Both the toothed collar and the rod 7' have vertical teeth, in contrast to the diagonally toothed engagement between 7 and 8 of Figure 1. The hub of the toothed collar 22 is provided with diagonally directed grooves 23 which engage with complementary ridges 24 on the sleeve 9'. That end of the sleeve which is remote from the drive rests on a shoulder 25 of the housing, thus securing the sleeve against longitudinal displacement. That end of the spring 12' which is remote from the drive abuts against an annular spring plate 30, the end surface of which rests against a collar part 31 of the sleeve 9' and also against a shoulder 32 of the housing 1.

55

By the adjustment of the spindle 20 the toothed collar is axially displaced by the sliding-plate 21 with the result that the sleeve 9' is annularly displaced together with the piston. The adjustment 5 of fuel supply is effected in the same manner as in the first example of construction.

The hub of the toothed collar 22 can be provided with diagonally directed ridges instead of grooves, which ridges engage in complementary 10 grooves or slots in the sleeve 9'. Instead of the spindle 20 an eccentric pin engaging in a groove may be used in this form of construction as in Figure 1.

In the examples shown, the adjustment of fuel 15 supply from without, by means of the eccentric pin or the spindle, merely alters the conclusion of fuel injection of the individual pump in question, in relation to the other pumps, because that edge of the piston which regulates the commencement of fuel injection lies in a plane at right angles to the axis of the piston. If this 20 edge of the piston were also a diagonal edge and if it were parallel to the diagonal edge controlling the conclusion of injection, then the adjustment 25 devices as described would effect an adjustment of the commencement of injection without affecting the amount of fuel delivered by the pump in question, in relation to the other pumps. In this case the displacement of the governor rod 30 would simply effect a uniform adjustment of the commencement of injection of all the pumps. However, if the two diagonal edges corresponding to commencement of injection and conclusion of 35 injection are not parallel, then adjustment either through the governor rod or through the adjustment device will result in an alteration of the amount of fuel delivered and of the commencement of injection.

We declare that what we claim is:

- 40 1. A fuel injection pump for internal combustion engines comprising in combination a housing, a cylinder disposed in said housing and provided with inlet and outlet openings, a piston, provided with valve means cooperating with said openings, axially displaceable within the cylinder to provide a pumping effect and rotatively displaceable relative to the cylinder to control the pumping effect, an intermediate member disposed coaxially with the piston and rotatively displaceable therewith, a control rod in geared relationship with said intermediate member whereby the intermediate member and piston may be rotated by means of a displacement of the control rod, means whereby axial displacement 45 of the intermediate member relatively to the cylinder provides a rotative displacement of the piston without displacement of the control rod, and means for axially adjusting the position of the intermediate member.
- 50 2. A fuel injection pump for internal combustion engines comprising in combination a housing, a cylinder disposed in said housing and provided with inlet and outlet openings, a piston, provided with valve means cooperating with said openings, axially displaceable within the cylinder to provide a pumping effect and rotatively displaceable within the cylinder to control the pumping effect, an intermediate member consisting of two elements disposed coaxially with the piston, of which the 55 first element is adapted for engagement with the piston so as to be rotatively displaceable therewith and is arranged to engage the second element so that a relative longitudinal displacement of the two elements produces a dependent relative rotative displacement; a control rod in geared relationship with the second element of the intermediate member whereby the intermediate member and piston may be rotated by means of a displacement of the control rod, and means for axially adjusting the position of the second element.
- 60 3. A fuel injection pump according to claim 4 in which the spring for urging one end of the first element towards the shoulder is constituted by the piston return spring aforesaid.
- 65 4. A fuel injection pump for internal combustion engines comprising in combination a housing, a cylinder disposed in said housing and provided with inlet and outlet openings, a piston, provided with valve means cooperating with said openings, axially displaceable within the cylinder to provide a pumping effect and rotatively displaceable within the cylinder to control the pumping effect,

relationship with the second element of the intermediate member whereby the intermediate member and piston may be rotated by means of a displacement of the control rod, and means for axially adjusting the positions of the elements of the intermediate member relatively to each other.

3. A fuel injection pump for internal combustion engines comprising in combination a housing, a cylinder disposed in said housing and provided with inlet and outlet openings, a piston, provided with valve means cooperating with said openings, axially displaceable within the cylinder to provide a pumping effect and rotatively displaceable within the cylinder to control the pumping effect, an intermediate member consisting of two elements disposed coaxially with the piston, of which the first element is adapted for engagement with the piston so as to be rotatively displaceable therewith and is arranged to engage the second element through diagonal claw couplings formed on complementary faces of the elements so that a relative longitudinal displacement of the two elements produces a dependent relative rotative displacement, a control rod in geared relationship with the second element of the intermediate member whereby the intermediate member and piston may be rotated by means of a displacement of the control rod, and means for axially adjusting the positions of the elements of the intermediate member relatively to each other.

4. A fuel injection pump for internal combustion engines comprising in combination a cylinder provided with inlet and outlet openings, a piston, provided with valve means cooperating with said openings, axially displaceable within the cylinder to provide a pumping effect and rotatively displaceable within the cylinder to control the pumping effect, a rotatable cam for displacing the piston axially within the cylinder in one direction, a piston return spring for displacing the piston axially within the cylinder in the opposite direction; and intermediate member consisting of two elements disposed coaxially with the piston, of which the first element has two ends and is mounted outside the cylinder and is adapted for engagement with the piston so as to be rotatively displaceable therewith, and is arranged to engage the second element through diagonal claw couplings formed on complementary faces of the elements so that a relative longitudinal displacement of the two elements produces a dependent relative rotative displacement; a housing for the cylinder, a shoulder disposed within said housing so as to abut the first element of the intermediate member, a spring for urging that end of the first element more remote from the rotatable cam towards the shoulder, a control rod in geared relationship with the second element of the intermediate member whereby the intermediate member and piston may be rotated by means of a displacement of the control rod, and means for axially adjusting the position of the second element.

5. A fuel injection pump according to claim 4 in which the spring for urging one end of the first element towards the shoulder is constituted by the piston return spring aforesaid.

6. A fuel injection pump for internal combustion engines comprising in combination a housing, a cylinder disposed in said housing and provided with inlet and outlet openings, a piston, provided with valve means cooperating with said openings, axially displaceable within the cylinder to provide a pumping effect and rotatively displaceable within the cylinder to control the pumping effect,

- an intermediate member disposed coaxially with the piston and rotatively displaceable therewith, a control rod in geared relationship with said intermediate member whereby the intermediate member and piston may be rotated by means of a displacement of the control rod, means whereby axial displacement of the intermediate member relatively to the cylinder provides a simultaneous rotative displacement of the intermediate member and of the piston without displacement of the control rod, and means for axially adjusting the position of the intermediate member.
7. An injection pump according to claim 6 which includes a diagonally toothed rod and a complementary diagonal toothing on the intermediate member.
8. An injection pump according to claim 1 wherein the means for axially adjusting the position of the intermediate member comprises a pair of substantially parallel surfaces disposed around part of the circumference of the intermediate member and an adjusting element engaging the intermediate member between the pair of surfaces.
9. An injection pump according to claim 1 wherein the means for axially adjusting the position of the intermediate member comprises a pair of substantially parallel surfaces disposed around part of the circumference of the intermediate member and a pin passing through the housing and having an eccentric projection which engages the intermediate member between the pair of surfaces.
10. An injection pump according to claim 1 wherein the means for axially adjusting the position of the intermediate member comprises a pair of substantially parallel surfaces disposed around part of the circumference of the intermediate member, a pin passing through the housing and having an eccentric projection at one end, and a sliding piece through which the eccentric projection of the pin engages the intermediate member between the pair of surfaces aforesaid.
11. An injection pump according to claim 1 wherein the means for axially adjusting the position of the intermediate member comprises a pair of substantially parallel surfaces disposed around part of the circumference of the intermediate member, a rotatable pin passing through the housing having an eccentric projection at one end which engages the intermediate member between the pair of surfaces and having a circumferential shoulder disposed approximately at mid-length and a threaded member arranged for threadedly engaging the housing so as to be disposed coaxially with the pin and to abut the shoulder of the pin for locking said pin in any rotational position.
12. An injection pump according to claim 1 wherein the means for axially adjusting the position of the intermediate member comprises a pair of substantially parallel surfaces disposed around part of the circumference of the intermediate member, an adjusting spindle disposed in the housing substantially parallel to the axis of the cylinder, and a sliding element attached to one end of the spindle and adapted for engagement with the intermediate member between the pair of surfaces.
13. An injection pump according to claim 2 wherein the means for axially adjusting the position of the intermediate member comprises a pair of substantially parallel surfaces disposed
- around part of the circumference of the intermediate member, a rotatable pin passing through the housing having an eccentric projection at one end which engages the intermediate member between the pair of surfaces and having a circumferential shoulder disposed approximately at mid-length and a threaded member arranged for threadedly engaging the housing so as to be disposed coaxially with the pin and to abut the shoulder of the pin for locking said pin in any rotational position.
14. An injection pump according to claim 2 wherein the means for axially adjusting the position of the intermediate member comprises a pair of substantially parallel surfaces disposed around part of the circumference of the intermediate member, an adjusting spindle disposed in the housing substantially parallel to the axis of the cylinder, and a sliding element attached to one end of the spindle and adapted for engagement with the intermediate member between the pair of surfaces.
15. A fuel injection apparatus for multicylinder internal combustion engines comprising in combination a housing, a plurality of pump cylinders disposed in said housing and each provided with inlet and outlet openings, a piston provided with valve means cooperating with said openings, axially displaceable within each pump cylinder to provide a pumping effect and rotatively displaceable to control the pumping effect of the cylinder, an intermediate member disposed coaxially with each piston and rotatively displaceable therewith, a common control rod in geared relationship with all the intermediate members whereby all the intermediate members and pistons may be rotated by means of a displacement of the control rod, means whereby axial displacement of any of the intermediate members relatively to the corresponding pump cylinder provides a rotative displacement of the corresponding piston without displacement of the control rod, and means for axially adjusting the position of every intermediate member individually.
16. A fuel injection apparatus for multicylinder internal combustion engines comprising in combination a housing, a plurality of pump cylinders disposed in said housing and each provided with inlet and outlet openings, a piston provided with valve means cooperating with said openings, axially displaceable within each pump cylinder to provide a pumping effect and rotatively displaceable to control the pumping effect of the cylinder, a plurality of intermediate members each consisting of two elements disposed coaxially with each piston, of each of which intermediate members the first element is adapted for engagement with the corresponding piston so as to be rotatively displaceable therewith and is arranged to engage the second element so that a relative longitudinal displacement of the two elements produces a dependent relative rotative displacement, a control rod common to all the pump cylinders in geared relationship with each second element of the intermediate members whereby all the intermediate members and pistons corresponding thereto may be rotated by means of a displacement of the control rod, and means for effecting separately axial adjustment of the positions of the respective elements of every individual intermediate member relatively to each other.
